(57) **CLAIM**

The ornamental design for a medical dressing, as shown and described.

DESCRIPTION

FIG. 1 is a top perspective view showing a first embodiment of a medical dressing, the oblique line shading representing transparency;

FIG. 2 is a partially exploded perspective view thereof as it may appear with release liners removed;

FIG. 3 is an exploded perspective view thereof;

FIG. 4 is an enlarged right side elevation view thereof;

FIG. 5 is an enlarged left side elevation view thereof;

FIG. 6 is an enlarged front elevation view thereof;

FIG. 7 is an enlarged rear elevation view thereof;

FIG. 8 is a top plan view thereof;

FIG. 9 is a bottom plan view thereof;

FIG. 10 is a perspective view thereof, with release liners removed, as it may appear when applied to a person;

FIG. 11 is a top perspective view showing a second embodiment of a medical dressing, the oblique line shading representing transparency;

FIG. 12 is a partially exploded perspective view thereof as it may appear with release liners removed;

FIG. 13 is an exploded perspective view thereof;

FIG. 14 is an enlarged right side elevation view thereof;

FIG. 15 is an enlarged left side elevation view thereof;

FIG. 16 is an enlarged front elevation view thereof;

FIG. 17 is an enlarged rear elevation view thereof;

FIG. 18 is a top plan view thereof;

FIG. 19 is a bottom plan view thereof;

FIG. 20 is a perspective view thereof, with release liners removed, as it may appear when applied to a person;

FIG. 21 is a top perspective view showing a third embodiment of a medical dressing, the oblique line shading representing translucency;

FIG. 22 is a partially exploded perspective view thereof as it may appear with release liners removed;

(Continued)

FIG. 23 is an exploded perspective view thereof;
 FIG. 24 is an enlarged right side elevation view thereof;
 FIG. 25 is an enlarged left side elevation view thereof;
 FIG. 26 is an enlarged front elevation view thereof;
 FIG. 27 is an enlarged rear elevation view thereof;
 FIG. 28 is a top plan view thereof;
 FIG. 29 is a bottom plan view thereof;
 FIG. 30 is a perspective view thereof, with release liners removed, as it may appear when applied to a person;
 FIG. 31 is a top perspective view showing a fourth embodiment of a medical dressing, the oblique line shading representing translucency;
 FIG. 32 is a partially exploded perspective view thereof as it may appear with release liners removed;
 FIG. 33 is an exploded perspective view thereof;
 FIG. 34 is an enlarged right side elevation view thereof;
 FIG. 35 is an enlarged left side elevation view thereof;
 FIG. 36 is an enlarged front elevation view thereof;
 FIG. 37 is an enlarged rear elevation view thereof;
 FIG. 38 is a top plan view thereof;
 FIG. 39 is a bottom plan view thereof; and,
 FIG. 40 is a perspective view thereof, with release liners removed, as it may appear when applied to a person.
 The oblique line shading shown in FIGS. 1-20 shows transparency. The oblique line shading shown in FIGS. 21-40 shows translucency.

The small circular broken lines shown in FIGS. 11-13, 18-20, 31-33, and 38-40 represent perforations and form no part of the claimed design.

The broken lines in FIGS. 10, 20, 30 and 40 depict environment that forms no part thereof.
